UNITED STATES PATENT OFFICE

150,271

DESIGN FOR A BOOKKEEPING MACHINE

Jan Streng, Mason, N. H., assignor to Remington Rand Inc., Buffalo, N. Y., a corporation of Delaware

Application August 10, 1946, Serial No. 132,428

Term of patent 14 years

(Cl. D64—11)

To all whom it may concern:

Be it known that I, Jan Streng, a citizen of the United States, residing in Mason, county of Hillsboro, and State of New Hampshire, have invented a new, original, and ornamental Design for a Bookkeeping Machine, of which the following is a specification, reference being had to the accompanying drawings, forming part thereof.

Figure 1 is a perspective view of a bookkeeping machine showing the new design as viewed from the right-hand side;

Fig. 2 is a front elevational view of the bookkeeping machine;

Fig. 3 is an enlarged partial plan view of Fig. 2;

Fig. 4 is a partial perspective view of the keyboard assembly;

Fig. 5 is a detailed perspective view of one of the tabulator keys.

The dominant feature of the invention resides in the bookkeeping machine keyboard illustrated in solid lines.

I claim:

The ornamental design for a bookkeeping machine, substantially as shown and described.

JAN STRENG.
